Thomas Muehleisen

BY *A. B. Bowman*
ATTORNEY.

UNITED STATES PATENT OFFICE.

THOMAS MUEHLEISEN, OF SAN DIEGO, CALIFORNIA.

WATER-HEATER.

1,291,083.

Specification of Letters Patent. Patented Jan. 14, 1919.

Application filed February 21, 1918. Serial No. 218,504.

To all whom it may concern:

Be it known that I, THOMAS MUEHLEISEN, a citizen of the United States, residing at San Diego, in the county of San Diego and State of California, have invented certain new and useful Improvements in Water-Heater-Coil Mechanism, of which the following is a specification.

My invention relates to coils for water heaters and the means for connecting said coils, and the objects of my invention are: First, to provide a water heater coil in which the water from the service pipe circulates upwardly and downwardly through the heater coils so that the water circulates toward the heat and approximately twice the distance it does in the conventional heater coils. Second, to provide a means for connecting to the ordinary or conventional coil now in use, which will cause the water to circulate upwardly and downwardly and approximately twice the distance as the ordinary. Third, to provide a connection for both the top and the bottom of the coils which may be readily used in connection with the conventional coils now in use as well as with new coils; and fourth, to provide a water heater coil mechanism which is simple and economical of construction, durable, easy to install, easy to repair, very efficient in its action and will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this specification, in which:

Figure 1 is a sectional view of a heater casing and showing my coil mechanism in position therein ready for use, showing a portion thereof in section and a portion in elevation to facilitate the illustration. Fig. 2 is a top view thereof with the top of the heater casing removed. Fig. 3 is a longitudinal sectional view on an enlarged scale of the lower connecting member for connecting the regular water service pipe and the heated water pipe with the lower end of the coil and Fig. 4 is a similar sectional view of the connecting member for connecting the upper ends of the coils together.

Similar characters of reference refer to similar parts throughout the several views of the drawings.

It will be here noted that I have shown and illustrated a double coil for water heaters but that a triple coil may be used with but slight changes in the connection without departing from the principle involved and it will be further noted that the structure herein may be used either for circulating the water through two coils or through a single coil by simply changing the service pipe connection to my connecting members.

The inner coil 1, outer coil 2, lower connecting member 3, and upper connecting member 4, constitute the principal parts of my coil mechanism.

The coils 1 and 2 are positioned the one inside of the other in the conventional manner and they are rigidly secured into the member 3, preferably by brazing. The member 3 is shaped as shown best in Figs. 1 and 3 of the drawings provided with a partition 3^a separating said member into two compartments or passage ways and the lower ends of the coils 1 and 2 connect with these separate passages 3^b and 3^c, a portion 3^d of this member 3 is round and reduced leaving a shoulder 3^e to rest against the inside surface of the heater casing and this reduced portion is provided with an external thread 3^f adapted for the nut 3^g which is a lock nut adapted to secure this connecting member 3 rigidly to the casing thus supporting the coils in position. Communicating with the passage 3^b in the reduced portion 3^d is a pipe 5 which leads to the ordinary water system, and connecting with the passage 3^c is a service pipe 6 connected with receptacle or fixture in which the hot water is to be used. In the outwardly extending end of the member 3 is a plug 3^h forming a dead end in that end of the member 3. The connecting member 4 is a hollow casting provided with holes adapted for the upper end of the coils 1 and 2 which are secured thereto, preferably by brazing and it is provided with an upwardly extending portion in which is secured an ordinary pipe plug 4^a so that when this pipe plug is in position the water circulates from the upper end of the coil 1 into the coil 2 and down through the coil 2 through the passage 3^b and into the service pipe 6. If however, it is desired to use the coil in the conventional manner the holes to which the pipes 5 and

6 are connected may be plugged and the service pipe connected in the place of the plug 3rd. The plug 4th removed and the hot water service pipe 6 is placed therein 5 instead of the plug 4th and the water from the ordinary water system will then circulate from the bottom of each coil to the top and out in the ordinary or conventional manner.

10 Though I have shown and described a particular construction, combination and arrangement of parts and portions I do not wish to be limited to this particular construction, combination and arrangement but 15 desire to include in the purview of my invention and construction, combination and arrangement substantially as set forth in the appended claims.

It is obvious that with this construction 20 there is provided a coil mechanism in which a small coil space may be utilized so that the water is heated to approximately double the temperature thus, adding to the efficiency of the same size coil space; that the mechanism 25 may be readily changed to either single or double circulation as desired that the mechanism as a whole is simple, and economical of construction, durable and efficient.

30 Having thus described my invention what I claim as new and desire to secure by Letters Patent, is:

1. In water heater coil mechanism, means for connecting the lower end of the coil 35 separately or jointly with a water service pipe, comprising a fitting provided with channels therein communicating with the separate coils, means for connecting a cold water service pipe with one of said channels 40 and a hot water service pipe with another of said channels and means for connecting the service pipe with both of said channels instead of with the separate channels as desired.

45 2. In water heater coil mechanism, means for connecting the lower end of the coil

separately or jointly with a water service pipe, comprising a fitting provided with channels therein communicating with the separate coils, means for connecting a cold water service pipe with one of said channels and a hot water service pipe with another of said channels, means for connecting the service pipe with both of said channels instead of with the separate channels as desired, and means for connecting the upper ends of said coils, whereby water will circulate from one coil to the other, and means for connecting said connection with the service pipe, whereby the water will circulate 60 upwardly in one coil and downwardly in the other or upwardly through both coils and out in to the service pipe.

3. In a water heater coil mechanism, the combination with a plurality of water heater 65 coils, of means secured to the lower ends of said coils provided with separate channels therein, communicating with the separate coils of the water heater, a cold water service pipe communicating with one of said 70 channels, a hot water service pipe communicating with another of said channels, means for connecting both of said channels to the service pipe in lieu of the separate hot and cold water service pipes, 75 means for connecting the upper ends of said coils and means for connecting said connection with the hot water service pipe, or closing it to said hot water service pipe as desired, whereby the water may be made to 80 circulate from the cold water service pipe upwardly in one of said coils and downwardly in another of said coils and to the hot water service pipe or may be made to circulate upwardly through said coils and out 85 through the upper connection to the service pipe as desired.

In testimony whereof, I have hereunto set my hand at San Diego, California, this 13th day of February, 1918.

THOMAS MUEHLEISEN.
